UNITED STATES PATENT OFFICE

2,455,191

RADIO WAVE DETECTOR SYSTEM

Claude Langdon Richards, London, England, assignor to The Mullard Radio Valve Company Limited, London, England

Application November 18, 1944, Serial No. 564,085
In Great Britain July 30, 1943

Section 1, Public Law 690, August 8, 1946
Patent expires July 30, 1963

5 Claims. (Cl. 250—27)

1

This invention relates to radio receiving circuits and aims at the provision of a circuit capable of functioning alternatively in any one of a plurality of ways.

According to the invention a radio receiving circuit is provided with simple switch means whereby at the will of the operator it can be adjusted to receive information conveyed by radiation in any one of two or more different forms, e. g. as amplitude modulation or as frequency modulation of a carrier wave. It is a feature of the invention that the switch means may be incorporated in the L. F. stage or stages of the circuit. It is more especially intended that one of the forms of radiation from which a circuit according to the invention is capable of extracting information shall be a frequency-modulated carrier wave and for this purpose the circuit includes discriminator means, preferably arranged in the manner described in the specification of co-pending patent application currently filed by me for "Frequency Modulated Receivers", Serial No. 564,086, now Patent No. 2,415,656, issued February 11, 1947, according to which the output from a limiter is applied to an inductance (primary) which is coupled with another inductance (secondary), the primary or the secondary or both forming part of a tuned circuit adjusted to the unmodulated carrier frequency, and a connection is provided between the limiter output circuit and the secondary circuit whereby a carrier frequency component from one circuit is added vectorially to a carrier frequency component from the other circuit, which components are 90° out of phase when the carrier frequency and the tuned circuit (or circuits) are exactly in tune, the phase angle varying on either side of 90° as the carrier frequency is greater or smaller than the tuned frequency the resultant of the components being applied to a rectifier circuit comprising a single diode. The invention contemplates the use of a single channel (wholly or in part) for the reception of each of the various transmissions which the circuit is capable of receiving, rather than the use of separate and distinct channel for each form, and in this connection one feature of novelty introduced by the invention comprises the application, for the reception of C. W. radiation, of a modulating voltage to the anode of a valve which functions as part of the frequency discriminating circuit during reception of F. M. radiation. Further, circuits according to the invention may be adapted to provide automatic volume control; and where they are designed to receive, as one form of

2

radiation, a continuous wave transmission, the circuits are arranged so that a heterodyne beat-note can be applied to the detector without interfering with the A. V. C. provided. It will be noted from the description below of forms which the invention may assume that these various functions are achieved by the use of fewer valves and components than have been necessary in circuits heretofore proposed to provide some of these functions.

In order that the invention may be more readily understood certain embodiments thereof will now be described with reference to the accompanying drawing in which

15 Fig. 1 is a schematic diagram showing one form of a circuit according to the invention.

Fig. 2 is a schematic diagram showing another form of a circuit according to the invention and

20 Fig. 3 is a schematic diagram illustrating a further embodiment of the invention.

25 In the circuit embodying the invention shown in Fig. 1 the valve V_1 together with the associated elements L_p, L_s, C_s form a limiter-discriminator circuit for reception of F. M. waves, and is substantially identical with the circuit described in the aforementioned specification of co-pending patent application, Serial No. 564,086, now U. S. Patent 2,415,656, issued February 11, 1947, referred to above. The F. M. waves derived from

30 the preceding stages of the receiver are applied to a primary winding 8 of a L-F transformer 7, the secondary circuit 9 of which has one terminal connected to the grid 10 of tube V_1 and the other terminal connected to the cathode 11 and ground

35 through a resistor 16 shunted by capacitor 17 which resistor effects amplitude limiting of the F. M. wave in the tube V_1 in known manner. Connected in the anode circuit of tube V_1 is the winding L_p , which winding is magnetically coupled

40 to the circuits L_s, C_s , tuned to the center frequency of the applied wave and is also connected to one end of said circuit through capacitor 14. As pointed out in the above-referred to copending application, by interconnecting and magnetically coupling the winding L_p, L_s , a resulting

45 voltage is obtained comprising two components which are in quadrature with respect to each other when the applied wave has an instantaneous frequency equal to the resonant of the tuned circuit. At frequencies of the applied wave deviating from the center frequency, variations of the relative phase relationship of the two components are produced, thereby correspondingly varying the amplitude of the resultant. The resultant signal is applied to the

diode anode 13 having a load resistor 15 across which the modulation signal appears.

A three-way switch S has one contact F. M. connected to the output of the diode rectifier of the tube V_1 and the switch is thrown to this contact when frequency-modulated radiation is being received, the impulses being fed through a suitable filter circuit 18, 19 as shown to the audio output stage of the receiver.

When the circuit is to be used for reception of amplitude modulated signals the switch **S** is thrown to another contact thereof **AM** connected to the grid **10** of the pentode in the tube **V₁**. This grid is used as a diode from which **A. V. C.** and modulated signals are fed through suitable filter elements **20**, **21**, **22**, and **23**, as shown, respectively to preceding and subsequent stages of the receiver. When the valve is working in this manner the diode, and the other pentode elements in the tube **V₁** are inoperative.

For C. W. reception the switch S is thrown to the third contact thereof C. W. and a heterodyne signal obtained from a Hartley or other oscillator formed by the tube V_2 and the tuned circuit 24 is fed by direct coupling as shown, to the anode 12 of the tube V_1 as a modulating voltage. This heterodyne beatnote is rectified in the diode section 13-11 of the tube V_1 and supplied through the selector switch S to the later stages of the receiver. The oscillator tube V_2 is not in use except for C. W. reception and a switch H (which may be part of, or ganged to, the switch S) controls the supply of power thereto. As will be seen no heater current flows to the valve V_2 except when the circuit is used for C. W. reception.

C. W. Reception. The form of the invention shown in Fig. 2 is substantially identical with that shown in Fig. 1 save that for C. W. operation it is preferred to supply the local oscillator voltage to the diode section 13-14 of the discriminator tube V_1 through a suitable resistance R and a capacitor 27 rather than by direct coupling to the limiter anode as in Fig. 1. For satisfactory operation of the discriminator in F. M. reception the tuned circuits L_s , C_s must be very heavily damped and the resistance R assists in providing such damping.

A third form of the invention is shown in Fig. 3. Here, for C. W. operation, the local oscillator voltage developed across a load resistor 31 connected to anode 26 of tube V₂ is supplied through the intermediary of a resistor 29 and a capacitor 30 to the control grid of V₁ together with the incoming signal. The value of the voltage from the local oscillator V₂ is adjusted (for use during C. W. reception) to be equal to the carrier voltage at which 100% modulation just gives maximum power output. Interference with the A. V. C. operation is prevented by the resistances R₁, R₂ associated with the positive limiting diode D₂. Manual control of the volume may be effected by means of the variable resistance R₃, operation of which controls both the resultant L. F. signal from the diode D₁ and the bias voltage from the oscillator V₂ by way of the diode D₃ thereof. The latter voltage is employed as indicated at G. C. 2 to control in part the gain of the circuit, while as indicated at G. C. 1 the remainder of the gain is controlled automatically as previously described. It will be noted that various switch arms and associated contacts are provided to include or exclude various parts of the circuit according to the form of modulated radiation being received, and all may be ganged to, or form part of the switch S operating as

described above. The operation of the various switch arms is self-apparent from the drawings and is therefore not described in detail.

I claim:

- 5 1. A detector system for a carrier wave having
a predetermined central frequency, comprising
a discharge tube having a cathode, an anode
and a control grid interposed between the cathode
and the anode, an input circuit for the carrier
wave connected between the control grid and the
cathode, a resistance element and a condenser
element connected in shunt with each other and in
series with the control grid and the cathode for
producing grid circuit limiting of the carrier
wave and for generating a potential proportional
10 to the amplitude of the carrier wave, a transformer
having a primary winding in the output circuit of
said anode and a secondary winding, said secondary
winding being tuned to substantially the said
predetermined frequency and being magnetically
coupled to said primary winding to produce a terminal
voltage in quadrature with the voltage of the primary
winding, means to interconnect one end of each
20 of said windings to thereby combine the voltage
of the primary winding and said terminal voltage
to produce a resultant voltage, means for rectifying
said resultant voltage to produce a potential
proportional to the amplitude of said re-
25 sultant voltage, a heterodyne oscillator coupled to
said discharge tube, means to energize said dis-
charge tube and said heterodyne oscillator, an
output circuit, and means to selectively connect
the output circuit to said means for generating a
30 potential proportional to the amplitude of the
carrier wave and said means to generate a potential
proportional to the amplitude of said
resultant voltage and to selectively energize said
heterodyne oscillator.

35 2. A detector system for a carrier wave having
a predetermined central frequency, comprising a
discharge tube having a cathode, an anode and a
control grid interposed between the cathode and
the anode, an input circuit for the carrier wave
40 connected between the control grid and the cathode,
a resistance element and a condenser element
connected in shunt with each other and in
series with the control grid and the cathode for
producing grid circuit limiting of the carrier wave
45 and for generating a potential proportional to
the amplitude of the carrier wave, a transformer
having a primary winding in the output circuit of
said anode and a secondary winding, said secondary
winding being tuned to substantially the said
50 predetermined frequency and being magnetically
coupled to said primary winding to produce a terminal
voltage in quadrature with the voltage of the primary
winding, means to interconnect one end of each
of said windings to thereby combine the voltage
55 of the primary winding and said terminal voltage
to produce a resultant voltage, means for rectifying
said resultant voltage to produce a potential
proportional to the amplitude of said
resultant voltage, a heterodyne oscillator
60 coupled to the anode of said discharge tube,
means to energize said discharge tube and said
heterodyne oscillator, an output circuit, and
means to selectively connect the output circuit
to said means for generating a potential proportional
65 to the amplitude of the carrier wave and said
means to generate a potential proportional to
the amplitude of said resultant voltage and to
selectively energize said heterodyne oscillator.

70 3. A detector system for a carrier wave having

a predetermined central frequency, comprising a discharge tube having a cathode, an anode and a control grid interposed between the cathode and the anode, an input circuit for the carrier wave connected between the control grid and the cathode, a resistance element and a condenser element connected in shunt with each other and in series with the control grid and the cathode for producing grid circuit limiting of the carrier wave and for generating a potential proportional to the amplitude of the carrier wave, a transformer having a primary winding in the output circuit of said anode and a secondary winding, said secondary winding being tuned to substantially the said predetermined frequency and being magnetically coupled to said primary winding to produce a terminal voltage in quadrature with the voltage of the primary winding, means to interconnect one end of each of said windings to thereby combine the voltage of the primary winding and the said terminal voltage to produce a resultant voltage, means for rectifying said resultant voltage to produce a potential proportional to the amplitude of said resultant voltage, a heterodyne oscillator coupled to the control grid of said discharge tube, means to energize said discharge tube and said heterodyne oscillator, an output circuit, and means to selectively connect the output circuit to said means for generating a potential proportional to the amplitude of the carrier wave and said means to generate a potential proportional to the amplitude of said resultant voltage and to selectively energize said heterodyne oscillator.

4. A detector system for a carrier wave having a predetermined central frequency, comprising a discharge tube having a cathode, an anode, a control grid interposed between the cathode and the anode and a diode anode, an input circuit for the carrier wave connected between the control grid and the cathode, a resistance element and a condenser element connected in shunt with each other and in series with the control grid and the cathode for producing grid circuit limiting of the carrier wave and for generating a potential proportional to the amplitude of the carrier wave, a transformer having a primary winding in the output circuit of said anode and a secondary winding, said secondary winding being tuned to substantially the said predetermined frequency and being magnetically coupled to said primary winding to produce a terminal voltage in quadrature with the voltage of the primary winding, means to interconnect one end of each of said windings to thereby combine the voltage of the primary winding and said terminal voltage to produce a resultant voltage, means to connect the

- other end of the secondary winding to said diode anode, a load resistance element interconnecting the diode anode and the cathode for producing a potential proportional to the amplitude of said resultant voltage, a heterodyne oscillator coupled to said discharge tube, means to energize said discharge tube and said heterodyne oscillator, an output circuit, and means to selectively connect the output circuit to said means for generating a potential proportional to the amplitude of the carrier wave and said means to generate a potential proportional to the amplitude of said resultant voltage and to selectively energize said heterodyne oscillator.
5. A detector system for a carrier wave having a predetermined central frequency, comprising a discharge tube having a cathode, an anode, and a control grid interposed between the cathode and the anode, an input circuit for said carrier wave connected between the control grid and the cathode, a parallel circuit arrangement comprising a resistance element and a capacitive reactance element connected in series with the control grid and cathode of said discharge tube to generate a potential proportional to the amplitude of said carrier wave, a transformer having a primary winding connected in the output circuit of said anode and a secondary winding, one of said windings being substantially tuned to said central frequency and said secondary winding being magnetically coupled to said primary winding to produce a terminal voltage in quadrature with the voltage across said primary winding, means to interconnect one end of each of said windings to combine the voltage of said primary winding and said terminal voltage to produce a resultant voltage, means for rectifying said resultant voltage to generate a potential proportional to the frequency deviations of said carrier wave from said central frequency value, an output circuit, and means selectively to connect said output circuit to said means for generating a potential proportional to the amplitude of the carrier wave and said means to generate a potential proportional to frequency deviations of said carrier wave.
